UNITED STATES PATENT OFFICE.

JOSEPH P. SMITHERS, OF BROOKLYN, NEW YORK; HERBERT SMITHERS AND WALTER SMITHERS EXECUTORS OF SAID JOSEPH P. SMITHERS, DECEASED.

AUTOMATIC STARTING DEVICE FOR MOTORS.

1,072,187.

Specification of Letters Patent.

Patented Sept. 2, 1913.

Application filed July 8, 1908. Serial No. 442,515.

To all whom it may concern:

Be it known that I, JOSEPH P. SMITHERS, a subject of the King of Great Britain, and a resident of Brooklyn, in the county of 5 Kings and State of New York, have invented certain new and useful Improvements in Automatic Starting Devices for Motors, of which the following is a specification.

My invention relates to automatic starting devices for internal combustion engines and has for its object to provide means for starting explosive engines operated by gas, gasoline or the like without the necessity of "cranking" or turning the engine over by 10 hand in order to give the engine its first impulse.

A further object of my invention is to provide a starting device which will be free from the crank-shaft of the engine at all 15 times except when it is desired to automatically start the engine or to rewind the starter after it has caused the engine to revolve by its own power.

To these ends my invention consists in 20 providing an automatic starting device for motors with means whereby it can be coupled to and uncoupled from the crank-shaft of an engine when the crank-shaft is idle or rotating.

My invention also consists in an automatic starting device for motors in which in the first step the starter is coupled to the engine shaft, in a further step a spring is released to rotate the engine shaft, in a further step 25 the spring is held from further unwinding but the starter still remains coupled to the engine shaft and in a final step, the starter is uncoupled from the engine shaft, all the steps being under the control of a single 30 operating lever or pedal.

My invention also consists in the novel means for re-winding the spring of the 35 starter and holding the same against unwinding.

My invention consists further in the details of construction and combinations of parts hereinafter more particularly described and then specified in the claim.

In the accompanying drawings, Figure 1 40 is a vertical section and partial elevation of a device constructed in accordance with my invention. Fig. 2 is a transverse vertical section taken on the line A, A, Fig. 1. Fig. 3 is a similar section taken on the line B, B, 45 Fig. 1. Fig. 4 is a top view of a detail.

Fig. 5 is a vertical section taken on the line C, C, Fig. 1 and illustrates the ratchet connection. Fig. 6 is a plan of a modification of the detail illustrated in Fig. 4. Fig. 7 is a vertical longitudinal section through a starting device constructed as a modification of my invention. Fig. 8 is a plan of a detail of construction as used in the modification illustrated in Fig. 7. Fig. 9 is a side elevation of a detail. Fig. 10 is a transverse vertical section taken on the line E, E, Fig. 7. Fig. 11 is a similar section taken on the line F, F, Fig. 7. Fig. 12 is a similar section taken on the line G, G, Fig. 7. Fig. 13 is a similar section through the roller-ratchet connection and taken on the line D, D, Fig. 7.

1 indicates the usual crank shaft of an internal combustion engine as used in automobiles, motor boats, and the like and is 50 provided at its end with a clutch member 2 fixed thereto.

In the preferred form of carrying out my invention, a casing, consisting of front and back plates or covers 3 and side walls 4, 55 entirely surrounds and protects the various parts of the device. Suitably journaled in the end plates 3 of the casing is a shaft 5 preferably in line with the crank-shaft 1 so as to form a continuation thereof and is 60 provided at its end adjacent to the crank-shaft with a clutch member 6 secured thereto against rotation independent of the shaft but capable of sliding longitudinally thereon to cause it to engage with or be disengaged 65 from its corresponding member 2. The clutch member 6 is moved longitudinally on the shaft 5 by means of a lever 7 provided with laterally projecting pins 8 which work 70 in a suitable groove in the member 6, the lever being suitably mounted on the casing 3 and operated in a manner to be presently described. While I have shown and prefer 75 to use a crab-clutch to couple the crank shaft and the starter, it will be obvious that other suitable forms of clutches might be used without departing from the spirit of my invention.

An internal gear wheel 9 is loosely mounted 80 on the shaft 5 and provided with an elongated hub 9' concentric with the shaft 5.

Interposed between the shaft 5 and the hub 9' are roller ratchets 10 working in eccentric slots 11, (see Fig. 5) and which couple the gear wheel 9 to the shaft 5 and 85

cause the shaft to be rotated by the gear wheel but; nevertheless, the shaft 5 cannot rotate the gear 9 as is well understood in the art. I prefer to use roller ratchets for coupling the gear 9 to the shaft 5 as by this construction great strength and silent running is obtained, but obviously other well known means for automatically coupling the gear 9 to the shaft might be employed as will readily suggest themselves to anyone skilled in the art and more especially as the shaft 5 only rotates during the very short space of time necessary to start the engine and rewind the mechanism.

15 12 indicates a coiled spring secured at one end to the hub 9' and at the other end to the casing 4, said spring being normally held under tension, so that upon freeing the spring it will unwind from the center and 20 rotate the hub 9' and the gear 9; it being rewound from the center by a reverse rotation of the gear wheel 9, the outer end of the spring being rigidly held to the casing.

25 Integral with or fastened to the gear wheel 9 so as to rotate therewith is a pinion 13 which meshes with a gear wheel 14 to which is secured a pinion 15 which is itself in mesh with a gear wheel 16 all of said gears being suitably mounted to run freely in 30 journals formed in the end plate of the casing.

35 The spring 12 when under tension, acts to rotate the gear-wheel 16 in the direction of the arrow, but is prevented from rotation by means of an eccentrically mounted roller 17 engaging a boss 18 on the gear 16. A link 19, secured to the stud to which the roller 17 is keyed, is pivotally connected to a lever 20 provided with a lug or projection 21 at the 40 end thereof. The eccentric roller 17 is normally held pressed against the boss 18 by the action of a spring 22.

45 23 indicates a pivotally mounted lever, preferably in the form of a foot-pedal and to which is pivoted a bar 24 provided with a depending lip 25 said lip being adapted to hit the projection 21 on the lever 20. The bar 24 passes loosely through the lever 7 and interposed between the lever 7 and lip 25 is 50 a compression spring 26. Upon drawing over the bar 24 the spring 26 is compressed and forces the two members of the clutch 2 and 6 together and couples the starter to the crank-shaft. Upon further movement of 55 the bar in the same direction the lip 25 hits the projection 21 and rotates the eccentric roller 17 which frees the gear 16 and allows the spring to unwind to start the engine.

60 The lever 23 reciprocates between stops 27 and 28 secured to a segment 29 and so arranged that when the lever strikes the stop 27 the lip 25 has hit the projection 21. The lever 23 is then freed and flies back due to the action of a spring 50, but is prevented 65 from returning to its original position

against the stop 28 by means of a detent 31 which enters a notch 30 in the segment 29. When the lever 23 comes to a stop at the notch 30 the lip 25 has freed the projection 21 which allows the eccentric roller 17 to return to position to engage the boss 18 on its return to position, but the return movement of the lever 23 has not been sufficient to draw the two members 2 and 6 of the clutch apart. The object of this construction is to 70 allow the roller 17 to hold the spring against further unwinding, but still leave the starter coupled to the crank-shaft, which is now rotating by its own power, to rewind the spring as will be presently described. Upon 75 freeing the detent 31 from the notch 30 the bar 24 makes a further backward movement which causes a collar 32 secured to the bar 24 to strike the lever 7 and force the members of the clutch apart and uncouple the 80 starter from the now rotating crank-shaft.

Obviously in order to normally hold the gear 16 from rotating a rack and detent might be employed, as illustrated in Fig. 6 instead of the eccentric roller or cam 17 and 85 its attendant boss on the gear 16.

38 indicates a pinion loosely mounted on the shaft 5 and provided with a number of laterally projecting lugs 34, said pinion meshing with a gear wheel 60 having a pinion 35 fixed thereto, which pinion meshes with the internal gear 9. It will thus be seen that when the spring unwinds the pinion 33 will rotate freely upon the shaft 5. A laterally projecting lug 36 extending from 100 the gear 16 at or near the outer edge rotates with the gear 16 when the spring is released and comes around and strikes the under side of an arm 37 secured to a rock shaft 38. The rock-shaft also carries a forked lever 39 which engages a collar 40 on the shaft 5. The collar 40 is keyed to the shaft 5 but capable of longitudinal movement thereon and is provided with a number of lateral projections or lugs 41 corresponding to the 105 lugs on the pinion 33, so that when the projection 36 strikes the under side of the arm 37, the collar 40 is locked to the pinion 33, thereby coupling said pinion to the shaft. This mechanism constitutes the means for 110 winding up the spring. The forked lever 39 is preferably constructed with a flexible or spring yielding shank as at 39' so that should the lugs on the collar 40 not coincide exactly with the notches on the pinion 33 115 when it is desired to couple the two together, the shank 39' will yield and store up energy to force the two members together when the lugs and notches do coincide which will take place upon a further revolution of the collar 40.

In the operation of the device, assuming that the spring has been previously wound up and is held under tension by the eccentric roller or cam 17, the operator forces 120

the lever 23 against the stop 27 which action first throws in the clutch members 2 and 6 and couples the shaft 5 to the crank shaft 1 and then releases the gear wheel 16 5 as previously described by turning the cam 17 in the direction of the arrow 42. The spring unwinding rotates the internal gear wheel 9 and its hub 9' which automatically couples to the shaft 5 by means of roller 10 ratchets 10 and causes the engine shaft 1 to be turned over when the usual cycle of the engine takes place and the shaft 1 is caused to rotate by power generated in the engine 15 itself as is usual in the art. As soon as the operator forces the lever against the stop 27 he releases the same which frees the lever 20 and allows the cam 17 to return to position to engage the boss 18 when the same returns to position opposite the cam, the lever 23 coming to rest at the notch 30 so 20 that the clutch still remains coupled as previously described.

When the shaft 5 rotates due to the unwinding of the spring, the gear 16 revolves 25 in the direction of the arrow until the lug 36 strikes the under side of the arm 37 which couples the collar 40, which is revolving with the shaft 5, to the pinion 33, free on the shaft, which rotates the internal 30 gear 9 in the reverse direction through gear 60 and pinion 35 and winds the spring, the gear 9 being free to rotate in the opposite direction to the direction of rotation of the shaft owing to the roller ratchet connection. When the collar 40 is coupled to the pinion 33, the gear 16 is also caused to rotate in the opposite direction to the direction when unwinding the spring and the lug 36 comes around and strikes the top of 35 the arm 37 and draws apart the collar 40 and pinion 33 which causes the winding up operation to cease. At the same time that the lug 36 throws out the winding mechanism, the rise or boss 18 is engaged by the 40 cam 17 and the gear 16 is held against the action of the spring. After the spring has been re-wound, which is after the engine has been running for a minute or so, the operator releases the lever 23 from the notch 30 45 and the starter is uncoupled and remains free from the engine until it is desired to again use it. This is a valuable feature as it prevents wear on the parts of the starting device due to its continued running with the engine, as is the case where the starter is securely fixed to the engine shaft.

Should the engine not take up under its

own power after being given the initial impulse by the starting device, the starter can be rewound by merely turning the shaft 5 60 by means of an ordinary starting crank placed on the exposed end of the shaft as usual, after which the starter can again be coupled to the crank-shaft and the spring released. Or, if desired to turn the engine 65 over by hand, the shaft 5 can be coupled to the crank shaft and turned over by a crank-handle on the end of the shaft 5, the spring 12 and attendant gearing not being affected by this hand-cranking.

In the modification illustrated in Fig. 7 and the following figures, the device operates in the same manner as the preferred form illustrated in Fig. 1. In this modification a spiral spring 51 is utilized to give 75 the initial impulse to the crank shaft and is preferably located in a separate casing 52 which may be mounted at a distance from the rest of the starting device. The spring is secured at one end to the casing 52 and 80 at the other to a shaft 53 which is connected by means of suitable sprocket wheels and a chain 54 to the internal gear wheel 9. In this modification the ratio of the train of gearing is different from that in the form 85 shown in Fig. 1 but the operation remains the same. The main advantages of a device constructed in accordance with the modification are that the starting device as a whole is cheaper to manufacture, the starter-box 90 proper is much smaller, and an extremely powerful spring can be utilized without having to excessively increase the size.

What I claim as my invention is:—

In an automatic starting device for motors, the combination of a shaft, a gear-wheel loosely mounted on said shaft, a spring normally held under tension, adapted to rotate said gear-wheel, means adapted to couple said gear-wheel to said shaft when 95 said spring is released and means actuated by the unwinding of said spring to automatically couple said gear-wheel to said shaft to cause said gear-wheel to rotate in the reverse direction to wind said spring to 100 start said shaft.

Signed at New York, in the county of New York and State of New York this 3rd day of July A. D. 1908.

JOSEPH P. SMITHERS.
